RECTIFIER TIMING CIRCUIT

Robert L. Haynes, Indianapolis, Ind., assignor to
 Radio Corporation of America, a corporation
 of Delaware

Application May 25, 1942, Serial No. 444,463

9 Claims. (Cl. 179—100.3)

This invention relates to current control systems and particularly to rectifier-filter combinations for translating alternating currents into direct currents having predetermined voltage variations with respect to the alternating current variations.

In the art of sound recording wherein alternating current signals are recorded on film, noise reduction is generally applied. In the application of noise reduction it is necessary to rectify the signal currents, the resulting direct currents being impressed upon the noise reduction portion of the recorder which may be either the light modulator itself or a shutter or shutters to control the average amount of light as the signal varies in amplitude. In order to impart the proper action to the noise reduction element during increases and decreases in the signal, timing elements having certain characteristics are provided. That is, since the noise reduction portion of a recording system varies the average value of the light beam striking the photoelectric cell during reproduction, these light variations should not be so rapid as to introduce noise into the reproduced sound. However, the noise reduction action should be fast enough to substantially avoid clipping the signal peaks at the beginning of signals. Also at the end of a signal, the action of the noise reduction element must be such as to avoid flutter at low frequencies or during low frequency modulations and at the same time close with sufficient rapidity so as to provide the maximum amount of noise reduction.

The present invention is directed to a noise reduction system which provides a particularly desirable closing action, the principal object of the invention being to facilitate and improve the recording of noiseless sound records.

Another object of the invention is to control the noise reduction action of a sound recording system in a particular predetermined manner.

A further object of the invention is to provide the noise reduction elements of a sound recording system with a slow response immediately after the end of or decrease in a sound signal followed by a rapid response.

A further object of the invention is to provide a noise reduction circuit having timing elements which produce a slow closing action over a predetermined time period followed by a more rapid closing action.

Although the novel features which are believed to be characteristic of this invention will be pointed out with particularity in the appended claims, the manner of its organization and the

mode of its operation will be better understood by referring to the following description read in conjunction with the accompanying drawings forming a part hereof, in which:

5 Fig. 1 is a schematic circuit diagram of a simple embodiment of the invention;

Fig. 2 is a graph illustrating the operation of the circuit shown in Fig. 1;

10 Fig. 3 is a schematic circuit diagram of another embodiment of the invention;

Figs. 4, 5, 6 and 7 are graphs showing the action of the circuit of Fig. 3;

15 Fig. 8 is a schematic circuit diagram of another embodiment of the invention employing a double rectifier arrangement;

Figs. 9, 10, 11 and 12 are graphs showing the action of the circuit of Fig. 8;

Fig. 13 is a schematic circuit diagram showing another modification of the invention;

20 Figs. 14, 15, 16 and 17 are graphs showing the operation of the circuit of Fig. 13.

Referring now to Fig. 1, which shows the general principal of the invention in its simplest form, an input transformer 55 has its secondary 25 connected through a charging condenser 56 across a rectifier 57 and a condenser 58, in parallel with which is a resistance 60 having a bias source of potential 61 in series. The usual low-pass filter resistance 19 and condenser 18 are 30 shown connected between condenser 58 and output terminals 21 to prevent rapid voltage fluctuations from being impressed on the load which is generally the grid of a vacuum tube. The voltage discharge characteristics of the above

35 circuit are illustrated in Fig. 2, wherein condenser 58 and resistance 60 may be given values so that the discharge rate is as shown in curve I when no bias 61 is employed. With the bias 61 of a certain value the discharge characteristic is as 40 shown in curve J. By using selected values of resistance 60 and bias 61, any desired characteristic between curves I and J may be obtained.

Although the use of the charging rectifier 56 normally prevents discharging beyond zero, rectifier 57 is shunted across condenser 58 and through which the current from the bias source 61 can flow after the voltage on condenser 58

45 has reached zero, to prevent any possibility that a small signal of peculiar wave form would permit the output of the circuit to go beyond zero or reverse, this being the sole function of rectifier 57. Neither of the characteristics I or J shown in Fig. 2 is particularly desirable since the voltage at the cessation of a signal should 50 decrease slowly for a short time interval to pre-

vent flutter and then decrease rapidly to obtain the maximum noise reduction. The principles of operation shown in Figs. 1 and 2 are utilized in the following circuits to produce these desirable results.

Referring now to Fig. 3, showing another form of the invention, an alternating current signal is impressed upon primary 5 of a transformer 6, secondary 7 of which is connected to a charging rectifier 9. The secondary 7 of transformer 6 is tapped, the voltage between points 11 and 12 after rectification by rectifier 9 being impressed across a condenser 15 and a resistance 16. The voltage generated across the entire secondary of transformer 6 between the points 11 and 21 after rectification by rectifier 9 is impressed across a condenser 23 and a resistance 24 over a rectifier 25. The usual low pass filter is shown by condenser 18 and resistance 19.

In the above circuit the resistance 16 is high compared with the resistance 24, so that condenser 15 discharging through resistance 16 will do so at a slow rate compared with the discharge rate of condenser 23 through resistance 24. To illustrate the rates of these discharges, reference is made to Fig. 4, wherein curve A represents the rate of voltage decrease across condenser 15, while curve B represents the rate of voltage decrease across condenser 23, both of these curves being of the exponential type. It will be noted that curve B is similar to curve I of Fig. 2. Neither of the voltage characteristics A or B is desirable for controlling a noise reduction element since curve A would permit too large an amount of transparent area to be present in the final print, introducing noise, while curve B would introduce flutter during the recording of low frequency signals. As mentioned above, the voltage variation desired, is a slow decrease for a short time interval after the signal ceases, and a rapid decrease thereafter. In Fig. 4 it will be observed that curve A provides the desired discharge rate immediately after cessation of the signal, while curve B provides a more desirable closing rate thereafter. This combination action is shown by the full curve in Fig. 5 and is obtainable with the circuit shown as follows:

Since the condenser 23 is charged to a higher voltage than condenser 15, preferably 40 percent higher, as it is across portion 11-21 of secondary 7, and condenser 15 is only across section 11-12, there will be an appreciable time interval before the decreasing voltage across condenser 23 reaches the value of the decreasing voltage across condenser 15. This point is shown at *a* in Figs. 4 and 5. Since the voltage across the condenser 23 is isolated from the load by the rectifier 25, the only effective voltage at terminals 27 is that of the condenser 15. Thus, between points *a* and *b* the voltage at terminals 27 will decrease slowly in accordance with curve A. However, at point *a* the condenser 15 will be able to discharge through resistance 16 and also through resistance 24 as the voltage across condenser 23 is less than the voltage across 15 and current can now flow through rectifier 25. The voltage at terminals 27 will now decrease rapidly substantially along the characteristic curve B of condenser 23 as shown between points *a* and *c* in Figs. 4 and 5, the complete discharge voltage characteristic being shown by the full line curve of Fig. 5.

A more rapid closing time than that between points *a* and *c* in Fig. 5 may be accomplished by placing a battery or similar source of energy in series with resistance 24 across condenser 23. As

shown in Fig. 1, the use of such a bias battery will produce a more rapid discharge of the condenser 23 as shown by curve C in Fig. 6, corresponding to curve J of Fig. 2, the complete discharge voltage characteristic being shown by the solid line curve in Fig. 7. The curve of Fig. 7 is made up of a section *a'-b'* comparable to section *a-b* of Figs. 4 and 5 and a section *a'-c'* comparable to section *a''-c''* of Fig. 6.

Referring now to Fig. 8, the invention is shown embodied in a double discharge circuit such as disclosed and claimed in E. W. Kellogg Patent No. 2,227,906 of January 7, 1941 (see Fig. 6 of patent). In this arrangement the input transformer 30 is connected to rectifiers 31 and 32 in parallel, rectifier 31 charging a condenser 34 and rectifier 32 charging a condenser 35, the condensers being separated by a resistance 36 while the filter resistance 19 and condenser 18 are connected as shown in Fig. 1. In this arrangement it is to be observed that a rectifier 37 is connected across condenser 34 in parallel with a series circuit comprising a resistance 38 and a bias source of potential 39 similar to the arrangement in Fig. 1.

To illustrate the voltage variation produced at the output terminals 27, reference is made to Figs. 9 to 12, inclusive, wherein Fig. 9 represents the discharge characteristic for condenser 34 without the potential source 39 and is similar to curve I of Fig. 2, while the curve in Fig. 10 represents the voltage discharge characteristic for the condenser 35 without the bias 39 in the circuit. Because the condenser 35 cannot start to discharge until the condenser 34 has discharged appreciably and then it must discharge through resistance 36, the curve of Fig. 10 shows a desirable slow starting discharge rate. However, the rate of discharge of condenser 35 thereafter is too slow to be desirable. To increase this later rate of discharge the bias source 39 is employed.

To illustrate the action of the circuit in Fig. 8 with the bias 39, reference is made to Figs. 11 and 12, wherein the curve shown in Fig. 11 shows a rapid discharge rate for the condenser 34 with the bias battery 39 in series with resistance 38 and is similar to curve J of Fig. 2. Since this discharge rate is now rapid, the discharge of condenser 35 will substantially follow, and the voltage decrease of condenser 35 will be as shown by Fig. 12. However, there is a possibility that with the use of the bias 39 small signals of peculiar wave form may cause the discharge to overshoot and reverse as pointed out above in connection with Fig. 1. Such action is prevented by the rectifier 37 which will pass current with a reverse voltage and thus short-circuit the condenser 34, preventing any reverse charge being placed thereon.

Referring now to Fig. 13, a combination of the system of Figs. 3 and 8 is illustrated, wherein the input transformer 40 has its secondary tapped to provide sections 41-42 and 41-43. Section 41-42 charges through a rectifier 45, a condenser 47 shunted by a resistance 50. The larger section 41-43 of transformer 40 charges a condenser 48 through rectifier 49 and a condenser 51 through rectifier 52, a resistance 53 separating condensers 48 and 51. Connected across condenser 48 is a resistance 54.

The operation of the above described circuit is illustrated in the graphs shown in Figs. 14, to 17, inclusive, which will now be referred to. The condenser 47 will discharge through the resistance 50 at a slow rate, as shown by the curve D of Fig. 14, this curve being similar to curve A of Fig. 4. Condenser 48 will discharge more rap-

idly through low resistance 54 as shown by curve E in Fig. 14 which is similar to curve B of Fig. 4 or curve I of Fig. 2. The condenser 51 will discharge similarly to condenser 35 of Fig. 8, as shown by curve F in Fig. 14, and in the curve of Fig. 10. In Fig. 15 the resulting voltage discharge across condenser 47 is illustrated, this full-line curve being a combination of curves D and F of Fig. 14. This characteristic is produced similarly to the manner of obtaining the curve of Fig. 5. That is, the condenser 47 and resistance 50 control the load voltage until the voltage across condenser 51 equals that of condenser 47, at which time the discharge of condenser 47 is through resistance 50 and the resistances 53 and 54 in parallel with resistance 50. The discharge voltage will then substantially follow curve F of Fig. 14.

As described in connection with Figs. 1, 3 and 8, if a bias voltage is used as shown in Figs. 1 and 8, the condenser 47 and resistance 50 combination will still have the same normal rate of discharge as shown by curve D in Fig. 16, while condenser 48 will have a more rapid discharge rate as shown by curve G and condenser 35 will have a discharge characteristic as shown by curve H. The combination of curves D and H will provide the final discharge voltage variation across terminals 27 as shown by the full-line curve in Fig. 17.

From the above description it is to be observed that by use of the above-described circuits any desired closing characteristic is obtainable, this characteristic being of a form wherein over a short period after the cessation of a signal, the voltage decrease upon the control tube is at a slow rate, followed by a more rapid discharge rate to insure maximum noise reduction without flutter.

I claim as my invention:

1. In a noise reduction circuit, the combination of a source of alternating currents, means for rectifying said alternating currents, a plurality of condensers charged by said rectified currents, means for individually controlling the rate of discharge of each of said condensers to produce a voltage variation which is the substantial combination of said individual discharge rates, and means for biasing one of said individual discharge rate controlling means for increasing the rate of discharge of one of said condensers to increase the normal rate of discharge thereof.

2. In a noise reduction circuit, the combination of a source of alternating currents, means for rectifying said alternating currents, a plurality of condensers charged by said rectified currents, means for individually controlling the rate of discharge of each of said condensers to produce a voltage variation which is the substantial combination of said individual discharge rates,

means for charging said condensers to different values, and a source of biasing potential for one of said individual discharge rate controlling means for increasing the normal rate of discharge thereof.

3. A noise reduction circuit comprising an input transformer having a tapped secondary winding, a charging rectifier, a plurality of condensers, means connecting one of said condensers to a position on said secondary to obtain a certain charge on said condenser, means connecting another of said condensers to another position on said secondary to obtain a different charge thereon, means shunting each of said condensers to obtain different discharge rates therefor, and means for isolating the discharge of one of said condensers from affecting the discharge of said other condenser until the charges on each of said condensers are equal.

20 4. A noise reduction circuit in accordance with claim 3 in which said last-mentioned means comprises a second rectifier in series with said condensers to provide a single direction discharge path for said condensers.

25 5. A noise reduction circuit in accordance with claim 3 in which means are provided in the discharge path of said higher charged condenser to increase the discharge rate thereof.

6. A noise reduction circuit comprising a transformer, a charging rectifier, a condenser adapted to be charged by rectified currents from said rectifier, a resistive discharge path including a resistor shunting said condenser, and a source of bias potential in said resistive discharge path for increasing the rate of discharge of said condenser.

30 7. A noise reduction circuit in accordance with claim 6 in which a rectifier is provided in shunt to said condenser and resistive discharge path to prevent a reverse charge on said condenser.

40 8. A noise reduction circuit comprising a transformer, a plurality of charging rectifiers, a respective plurality of condensers, each charged by an individual rectifier, a resistive discharge path including a source of bias potential for one of said condensers, and another condenser having a resistive discharge path for controlling the output voltage of said circuit, the discharge rate of said last-mentioned condenser being controlled 45 by the rate of discharge of said first-mentioned condenser over a last portion of its discharging time interval.

50 9. A noise reduction circuit in accordance with claim 8 in which a rectifier is provided in shunt to said first-mentioned condenser to prevent a reverse charge on said condenser.

ROBERT L. HAYNES.
